UNITED STATES PATENT OFFICE.

EDWARD K. PARKER, OF RANDOLPH, MASSACHUSETTS.

PORTABLE FIRE-EXTINGUISHER.

SPECIFICATION forming part of Letters Patent No. 364,667, dated June 14, 1887.

Application filed November 3, 1886. Serial No. 217,855. (No model.)

To all whom it may concern:

Be it known that I, EDWARD K. PARKER, a citizen of the United States, and a resident of Randolph, in the county of Norfolk and State 5 of Massachusetts, have invented new and useful Improvements in Portable Fire-Extinguishers, of which the following, taken in connection with the accompanying drawings, is a specification.

10 This invention relates to improvements in portable fire-extinguishers; and it consists in the combination and arrangement of parts, as will hereinafter be more fully shown and described, reference being had to the accompanying drawings, where—

15 Figure 1 represents a plan view of the improved fire-extinguisher. Fig. 2 represents a vertical longitudinal section of it, and Fig. 3 represents a cross section on the line A B shown 20 in Fig. 2.

Similar letters refer to similar parts wherever they occur on the different parts of the drawings.

25 *a* is the tank or receptacle for the chemical or other liquid that is used with the apparatus, such tank being tightly closed in its upper end by means of the cover *a'*, soldered or otherwise connected to the said tank *a*, as is usual in devices of this kind. Through a perforation 30 in the cover *a'* is inserted the short filling-tube *b*, that is soldered to the cover *a'* or otherwise attached tightly to the same, such filling-tube projecting downward a short distance below the cover *a'*, as shown in Fig. 2, so that 35 its lower open end shall become sealed by the liquid contents of the tank *a* when the latter is properly filled, and thus prevent the liquid contents of the tank *a* from splashing or spilling out during transportation.

40 *b'* is a removable screw-cap, by means of which the upper end of filling-tube *b* is closed after the tank has been filled. Between the under side of the cap *b'* and cover *a'*, I make on the pipe *b* a perforation, *b''*, (shown in Fig. 45 2,) to allow the air to enter the tank *a* in the ratio as the liquid within it is displaced.

To the bottom of the tank *a* is riveted or otherwise secured the valve-case *c*, having the inlet-opening *c'*, valve-seat *c''*, ball-valve *c''*, 50 chamber *c'*, delivery ball-valve *c''*, and valve-seat *c''*, as is common in apparatus of this kind.

c' is a wire bail or cage for the purpose of limiting the upward motion of the ball-valve *c''* in the usual manner.

d is the pump-cylinder, its lower end being 55 screwed tightly into the upper end of valve-case *c*, and its upper end projects through a perforation in the cover *a'*, where the latter and pump-cylinder *d* are united together by solder or other suitable means. *d'* is the cap in 60 the upper end of pump cylinder *d*, as usual, which cap has a central perforation, through which passes loosely the piston-rod *d''*, having handle *d''* in its upper end and piston *d'* in its lower end, as usual.

65 *d''* is a side perforation in pump-cylinder *d*, below the cap *d'*, to allow freedom of motion of the piston *d'* during its up-and-down motion, and also to permit any liquid that may pass above the piston *d'* to escape from cylinder *d* without going out the central cap-perforation, and thus preventing the wetting of the hand of the operator.

70 *e* is the air-chamber, the lower end of which is screwed into the upper end of the valve-case *c*, and having its upper end passing through a perforation in the tank-cover *a'* and soldered or otherwise tightly secured to the latter at this place.

75 *e'* is a cap screwed to the upper end of the air-chamber *e*, and having attached to and projecting through it the delivery-pipe *e''*, a portion of which projects above the cap *e'*, and to such portion is attached the hose-pipe *f*, as shown in Fig. 2.

80 The lower end of delivery-pipe *e''* is made bell-shaped or crowning, as shown in Fig. 2, and provided at such point with a series of outward or inclined projections, *e''* *e''*, between which are the slits, perforations, or openings 85 *e''* *e''*, as shown in Figs. 2 and 3. The projections *e''* *e''* serve as a guide and stop for the ball-valve *c''*, and the perforations or slits *e''* *e''* serve as passages through which the liquid passes from the lower part of air-chamber *e* 90 into the delivery-pipe *e''* during the downward stroke of the piston *d'*. To the exterior of the delivery-pipe *e''*, a short distance above its lower end, is secured a star or cross shaped piece, *e''*, (shown in Figs. 2 and 3,) the outside 95 dimensions of which are nearly equal to the interior diameter of the air-chamber *e*, and it 100

serves the purpose to keep the lower end of delivery-pipe e'' concentric within the air-chamber e , as shown in Figs. 2 and 3.

What I wish to secure by Letters Patent, 5 and claim, is—

The combination, in a portable fire-extinguisher, of the tank a , the valve-case c in the bottom thereof, the pump-cylinder d , secured to the valve-case, the vertical stationary air-chamber e , arranged outside the pump-cylinder and having its lower end secured in a fixed 10 position to the valve-case at one side the pump-cylinder, the fixed perforated centering-piece e^5 in the lower portion of the air-chamber, the ball-valve e^5 , and the stationary 15

delivery-pipe e'' , extending through the outer end of the air-chamber and having its lower end laterally slotted and expanded into a bell-shaped mouth, which receives and guides the ball-valve in its rising movement, substantially as described. 20

In testimony whereof I have signed my name to this specification, in the presence of two subscribing witnesses, on this 29th day of October, A. D. 1886.

EDWARD K. PARKER.
